 PLC**CLAIM**

The ornamental design for a synthesizer, as shown and described.

DESCRIPTION

FIG. 1 is a perspective view of a synthesizer showing my new design.

FIG. 2 is a front elevational view of the synthesizer of FIG. 1.

FIG. 3 is a rear elevational view of the synthesizer of FIG. 1.

FIG. 4 is a top view of the synthesizer of FIG. 1.

FIG. 5 is a bottom view of the synthesizer of FIG. 1.

FIG. 6 is a right side elevational view of the synthesizer of FIG. 1; and,

FIG. 7 is a left side elevational view of the synthesizer of FIG. 1.

The portions of the synthesizer shown in broken lines are understood to be for illustrative purposes only and form no part of the claimed design.
